UNITED STATES PATENT OFFICE.

JOHN BROWNING OGDEN, OF LYNCHBURG, VIRGINIA.

SOUND AND SHOCK ABSORBER.

1,036,313.

Specification of Letters Patent. Patented Aug. 26, 1912.

Application filed October 25, 1911. Serial No. 656,636.

To all whom it may concern:

Be it known that I, JOHN B. OGDEN, a citizen of the United States, residing at Lynchburg, in the county of Campbell and State of Virginia, have invented a new and useful Sound and Shock Absorber, of which the following is a specification.

This invention relates to sound and shock absorbers for typewriters, calculating machines, and the like, and has for its object the provision of means for attaching and supporting typewriters and other writing machines upon a table or desk in such manner that the machine shall be firmly secured to and yet be in the highest degree vibratory insulated therefrom, to the end that the noise of operation shall be reduced to a minimum, and the shock due to key and type bar impact shall be absorbed, and thus the consequent strain upon the nervous and muscular system of the operator, and also the wear and tear upon the machine, reduced, if not entirely eliminated.

The invention has for a further object the provision of means for adjusting the action of the absorbing device to suit the "touch" of the individual operator, and at the same time enabling the machine to be released from its position and reattached without disturbing such adjustment.

With the above and other objects in view, which will be readily apparent as the construction and operation is described, the invention consists in the novel construction of features, arrangement and combination of parts particularized in the appended claims, and which will now be described in detail in connection and with reference to the accompanying illustrative drawings showing the preferred embodiment of the invention with certain modification. It is to be understood, however, that while the drawings show a complete operative form of the invention, the latter is not confined to the exact construction illustrated.

In the drawings:—Figure 1 is a side elevation of a part of a typewriter frame with the invention in place. Fig. 2 is an end view of Fig. 1. Fig. 3 is a vertical section through a portion of the device with a part of the typewriter frame broken away to show the manner of attachment thereto. Figs. 4 and 5 are detail perspective views of modified forms of clamping clip. Fig. 6 is

a detail perspective view of the cushion spring and the foot of the machine.

In these drawings the numeral 1 indicates a metallic cup having its bottom centrally pierced for the reception of a screw 2, whereby it is securely held to the table top or other support 3. Within the cup 1 is snugly fitted a thimble 4 of rubber or other suitable resilient material, and within the recess 5 of the thimble is disposed a pad 6 of felt or the like which assists in absorbing the vibration and serves to prevent the bottom of the rubber thimble 4 from being cut by the lower end of the helical spring 7 which is seated thereon. This spring is of an outer diameter corresponding to the interior diameter of the thimble 4, and of an interior diameter corresponding to the outer diameter of the rubber foot 8 which is ordinarily employed as a support for typewriters, having its shank 9 seated in a recess 10 formed in the under side of the frame 11 of the typewriter. The length and resistance of the spring 7 is carefully calculated to be such that under the normal load of the machine the bottom of the frame 11 will occupy a position above and slightly spaced from the rim 12 of the thimble. Under ordinary conditions of use the vibration of the machine and consequent play of the spring will be within such limits that the bottom of the frame 11 will not impinge against the rim 12 and yet the rim of the thimble will serve as an emergency resilient stop under extraordinary conditions.

The invention as thus far explained presents a very sensitive means for reducing the vibration and sound of writing machines in use, the resilient rubber thimble, the felt pad, and the spring coöperating to produce these results in a very high degree. It has been found, however, that the vibration of a typewriter differs under the manipulation of different operators by reason of the nature of the "touch," as well as its force. It follows that devices adjusted to take up the vibration of a machine when operated by one person require a different adjustment in order to perfectly perform the same function for another. With this condition in view, my invention provides further for the adjustment of the tension of the shock absorber just described to adapt it to the exigencies of use under different circum-

stances. To this end I provide the rim of the cup 1 with an ear 13 with which is engaged the eye 14 of a link 15, the latter being mounted for axial movement within 5 alined apertures 16 and 17 formed in the angular offset portion of a clip 18 arranged to lie against the side face of the machine frame and to overlie the same and with rearward extensions 19 and engage the rear face 10 thereof with lips 20, the portion 19 being preferably provided with corrugations 21 in order to permit of expansion within certain limits and to engage frames of different width. A wing nut 22 is threaded upon 15 the projecting end of the link 15 and between said nut and the upper face of the angular offset portion 23 of the clip is disposed a helical adjusting spring 24.

By means of the nut 22 acting upon the 20 spring 24 the tension of the spring 7 is regulated, so that its sensitiveness is effectually controlled and adapted to the requirements of the operator. The clip and link serve at the same time as a convenient means of connecting the shock absorber to the typewriter 25 and enable the connection to be loosened without changing in any way the adjustment, the clip being merely lifted against the tension of the spring 24 out of engagement with the upper edge of the frame whereupon the typewriter may be lifted bodily out of the shock absorber.

The screws 2 may be omitted when it is not desired to fasten the machine to the table, in which case the connection between the shock absorber and machine frame would serve to couple them securely together while the machine is moved from place to place. The clip used may be that illustrated in Fig. 40 1, or where the shock absorber is in vertical alignment with an upright 25 of the machine frame that form of clip shown in Fig. 3 and in detail in Fig. 4 may be employed to advantage. Under some circumstances, also, 45 the form of clip shown in Fig. 5 may be employed. This clip is simple in form and has but one aperture for the guiding of the link 15, and in most cases is quite efficient.

In the device as a whole, the several parts 50 coöperate to practically eliminate vibration, including the rebound of the lower spring 7 and thimble 4. It will be observed that the downward impulse given the machine upon the striking of each key is resisted by 55 the members beneath the machine and, upon the recovery, the rebound of such resilient parts is gradually and progressively resisted by the spring 24, so that, in effect, the vibration is entirely absorbed and a state 60 of normal equilibrium maintained between the oppositely acting springs 7 and 24, the relation of which to the two extremes and its susceptibility to and the range of its disturbance is capable of sensitive adjustment to conform to the individuality of not

only the operator but of the machine as well, it being recognized that machines of the same make and to all appearances identical in construction have an individuality of their own and differ markedly in their response to the manipulation of their keys, wherefore vibratory insulators suited to the requirements of one machine are very often entirely unsuited to another. This difficulty is overcome, in the present case, by the provision of means for adjusting the reaction between the two oppositely acting springs of the sound and shock absorbing device. 70

What is claimed is:—

1. An attachment for writing machines 80 and the like provided with supporting feet, comprising a thimble of resilient material open at the top and closed at the bottom, a helical spring of an external diameter to enter the open end of the thimble and rest 85 upon the bottom thereof and of an internal diameter to snugly embrace the foot of the machine, the foot and spring both working within the thimble, the tension of the spring being so related to the weight of the machine 90 and the size and position of the thimble as to support the writing machine, under all conditions of use, with the open upper end of the thimble in spaced close relation to that portion of the frame of the machine 95 from which the foot projects.

2. An attachment for writing machines and the like having frames provided with supporting feet, comprising a thimble of 100 resilient material, a metallic cup adapted to seat the thimble and of a height to approach the open end of the thimble, a pad of yieldable material lodged within the thimble at the closed end thereof, and a helical spring having one end adapted to 105 the interior of the thimble and the other end of a diameter to closely embrace the supporting foot of the machine to which the attachment is applied, the spring and thimble being related to support the writing machine under normal conditions of use with the supporting foot of the machine entering the open end of the thimble, and with 110 said open end of the thimble in close relation to the frame of the machine adjacent the foot to engage the frame and serve as an elastic buffer for movements of the machine under the conditions of use.

3. A sound and shock absorber for writing machines and the like, comprising a resilient thimble, a helical spring mounted in the thimble, and a foot seated in the machine frame and projecting downwardly into engagement with the spring, in combination with a connection between the thimble and machine, comprising a link connected to the thimble, a clip to engage the machine frame, said clip having an angularly bent portion perforated to receive the 120 adjusting means on the end of the link, 125 130

and a compression spring interposed between said adjusting means and the angularly bent portion of the clip.

passing through the clip, and a spring mounted on the link and working in opposition to the spring within the thimble. 60

4. A sound and shock absorber for writing machines and the like, comprising a metallic cup, fastening means to secure the same to a suitable support, a rubber thimble closely fitting within the cup, a felt pad disposed in the bottom of the thimble, a helical compression spring mounted in the thimble upon the pad, a rubber foot having a shank seated in the machine frame with the foot portion projecting downwardly into engagement with the spring within the thimble, in combination with a connection between the thimble and machine comprising a link attached to the cup, a clip to engage the machine frame, said clip having an angular bent portion perforated to receive the link, an adjusting nut on the end of the link, and a compression spring interposed between said nut and the angularly bent portion of the clip.

7. An attachment for writing machines and the like having frames provided with supporting feet, comprising a thimble of resilient material, a metallic cup adapted to 65 seat the thimble and of a height to approach the open end of the thimble, and a helical spring having one end adapted to the interior of the thimble and the other end of a diameter to closely embrace the supporting 70 foot of the machine to which the attachment is applied, the spring and thimble being related to support the writing machine under normal conditions of use with a supporting 75 foot of the machine entering the open end of the thimble and with said open end of the thimble in close, spaced relation to the frame of the machine adjacent the foot to engage the frame and serve as an elastic buffer for movements of the machine under conditions 80 of use.

8. In a sound and shock absorber for writing machines and the like, a metallic cup, elastic means adapted to be interposed between the cup and the frame of the machine, and a connection between the metallic cup and the machine comprising a link attached to the cup, a clip to engage the machine frame and having an angularly bent portion perforated to receive the link, an 85 adjusting nut on the end of the link, and a compression spring interposed between said nut and the angularly bent portion of the clip. 90

9. A sound and shock absorber for writing machines and the like having supporting feet, comprising a thimble open at the top to receive a foot of the machine and having a closed bottom, a helical spring having one end adapted to enter the thimble and rest 100 upon the closed bottom and having the other end engaging a foot of the machine, a clip adapted to engage the frame of the machine at one side of and above the thimble, and a spring actuated link connection between the 105 clip and the thimble, whereby the machine frame is tied to the thimble, the spring of said link connection acting in opposition to the spring within the thimble.

In testimony, that I claim the foregoing 110 as my own, I have hereto affixed my signature in the presence of two witnesses.

JOHN BROWNING OGDEN.
